CLOTH-CUTTING MACHINE KNIFE
SHARPENER

Moe Steiner, Brooklyn, N. Y.

Application February 19, 1946, Serial No. 648,743

7 Claims. (Cl. 51—249)

1

This invention relates to new and useful improvements in cloth-cutting machines.

The invention more specifically relates to a cloth-cutting machine of the reciprocating knife type in which the knife is mounted on a cross-head which is reciprocated by a pitman connected with a crank on a flywheel driven by the motor of the machine. It is customary to have a hollow cover engaged over the crosshead, the pitman and the flywheel. An important object of this invention resides in providing the hollow cover with recessed bottom side portions for receiving grindstones for sharpening the knife. It is proposed to mount the knife forwards of the crosshead on a lug projecting from the crosshead so that the cover may be recessed as stated. With this construction it is possible to locate the grindstones directly above the knife, when they are not in use, and it is possible to provide a simple cam means which will move the grindstones towards and against the knife when they are lowered a sufficient distance so as to clear the bottom of the hollow cover.

Another important object of this invention resides in the construction of the cam means for controlling the inward and outward movements of the grindstones. It is also proposed that the cloth-cutting machine be provided with a vertical slide for moving the grindstones up and down along the knife for sharpening purposes. Another object of the invention resides in the provision of a vertical cylindrical member rotatively mounted on a support which is provided with guideways for said slide. It is proposed that the vertical cylindrical member be provided with an endless peripheral thread with a section thereof extending down and continuing into a section extending up and connecting with the top of said downwardly extending section. Means is provided for rotating said cylindrical member. It is proposed to mount a follower on the slide engaging said endless peripheral thread for reciprocating the slide.

Another object of this invention is to provide a main drive shaft for the grindstones arranged through a hollow coaxially in the cylindrical member referred to above. A thrust bearing is provided for said main drive shaft mounted on said slide so that the drive shaft will be extended downwards from and then be moved upwards back into the cylindrical member during the reciprocation of said slide. A drive is provided for driving said main drive shaft in all of its positions.

The invention also proposes horizontal arms

2

pivotedly mounted on the main drive shaft referred to above and supporting said grindstones in positions in which they are normally disposed in the recessed bottom side portions of the hollow cover previously mentioned. Drive transmissions connect the main drive shaft with the grindstones for driving them.

Another object of this invention resides in the construction of a particularly simple and efficient mechanism for operating the slide for moving the grindstones along the knife for sharpening purposes. It is proposed to characterize this mechanism by a friction drive wheel adapted to normally engage the flywheel of the cloth-cutting machine and connected for controlling the operation of the slide. It is proposed that the friction wheel be manually controlled for engaging the flywheel and that it be automatically disconnected from the flywheel after the slide 20 performs one complete cycle of its operation.

Another object of the invention is the construction of a device as described, which is simple and durable and which may be manufactured and sold at a reasonable cost.

25 For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a cloth-cutting machine constructed in accordance with this 35 invention.

Fig. 2 is a front view of Fig. 1.

Fig. 3 is a fragmentary enlarged vertical sectional view taken on the line 3—3 of Fig. 2.

Fig. 4 is a horizontal sectional view taken on 40 the line 4—4 of Fig. 3.

Fig. 5 is a horizontal sectional view taken on the line 5—5 of Fig. 3.

Fig. 6 is a fragmentary vertical sectional view taken on the line 6—6 of Fig. 3.

45 Fig. 7 is a fragmentary sectional view taken on the line 7—7 of Fig. 2.

The new and improved cloth-cutting machine, in accordance with this invention, includes the usual housing 10 having a base 11 and a standard 12. The standard 12 is formed with a vertical slot 14 in which the reciprocating knife 15 is mounted. The housing 10 is provided with a handle 16 by which it may be conveniently guided. An electric motor 17 is mounted on the top portion of the housing 10 and is controlled with the

usual switch 18. The electric motor 17 is connected to drive a flywheel 20 which is provided with a crank pin 21 connected with a pitman 22, in turn connected with a crosshead 23 which is vertically slidably engaged in guideways 24 mounted within the housing 10. The housing 10 has a small top handle 25 by which the cloth-cutting machine may be easily carried.

Up to this point the cloth-cutting machine is of standard construction. It now differs in the fact that the crosshead 23 is provided with a front lug 27 for supporting the knife 15. The upper end of the knife 15 engages the lug 27 and is releasably held by a fastening screw 28. A hollow cover 30 is mounted upon the front of the housing 10 and encloses the flywheel 20, the pitman 22, and the crosshead 23. Prior cloth-cutting machines are provided with hollow covers similar to the cover 30. However, this cover 30 distinguishes from the prior constructions in the fact that it is provided with recessed bottom side portions 31 adapted to form nooks into which the grindstones 32 engage in their inoperative positions. In prior constructions, the knife 15 is attached to the bottom of the crosshead 23. The purpose of mounting it to the front of the crosshead 23 is to place the edge of the knife 15 directly behind the recessed bottom side portions 31 so that the grindstones 32 are substantially in position for engaging the edge of the knife 15 when moved but slight distances towards each other. Furthermore, because the grindstones 32 are normally housed in the recessed bottom side portions 31 they do not project very far from the sides of the housing 10.

A guard bar 36 is positioned a slight distance to the front of the knife 15. This guard bar 36 is slidably mounted in spaced bearings 37 and 38 mounted on the front of the cover 30. A handle 39 is mounted on the top of the guard bar 36 by which it may be easily raised. A presser foot 40 is mounted on the bottom of the guard bar 36. The guard bar 36 is associated with means by which it may be latched in various elevated positions. This means includes a rod 42 turnably mounted in a bearing 43 which is on the front of the cover 30. A cam 44 is mounted upon the rod 42 and is engageable against the back of the guard bar 36 for forcing it forwards so as to frictionally bind it in the bearings 37 and 38. The outer end of the rod 42 is provided with a handle 45 by which the cam 44 may be disengaged from the guard bar 36 to free it. A spring 47 is connected with the handle 45 and with the cover 30 and acts to normally urge the cam 44 against the guard bar 36 for latching it in fixed positions.

A support 50 is fixedly mounted a short distance to the front of the cover 30 by a bottom bracket 51. A pair of top brackets 53 are mounted between the support 50 and the cover 30 and serve to assist in firmly holding the support 50. The support 50 is provided with vertical guideways 54. A vertical slide 55 slidably engages the guideways 54. This slide 55 is hollow and of semi-circular form and acts to house certain mechanism for vertically reciprocating the slide 55. This mechanism includes a vertical cylindrical member 56 which is rotatably supported at the top upon a bracket 57 and at the bottom upon a bracket 58. These brackets 57 and 58 are mounted upon the support 50.

The vertical member 56 is provided with an endless peripheral thread 59 having a section extending down and continuing into a section

extending up and connecting with the top of the downwardly extending section. A follower 60 is mounted on the slide 55 and engages the endless peripheral thread 59 for reciprocating the slide 55 when the vertical cylindrical member 56 is rotated. This follower 60 is in the nature of a fork 61 engaging the thread 59 and turnably supported by a shank portion 62 which engages into a hollow casing 63 which in turn is mounted upon the slide 55. A spring 64 is housed in the casing 63 and resiliently urges the fork 61 into engagement with the thread 59. The ends of the fork 61 are suitably beveled or pointed so as to permit the follower 60 to negotiate all the turns necessary to maintain contact with the thread 59 while the cylindrical member 56 is rotated. The shank portion 62 projects from the slide 55 and has an external knob 65 by which the shank portion 62 may be pulled outwards to disengage the fork 61 from the thread 59 to free the slide 55 which may then be removed from the guideways 54.

A worm wheel 66 is mounted upon the bottom end of the cylindrical member 56 and is engaged by a worm pinion 67 on a shaft 68 rotatively mounted between the bracket 58 and the support 50. A main drive shaft 70 for the grindstones 32 extends coaxially through the cylindrical member 56 which is hollow for this purpose. The drive shaft 70 is non-circular in transverse cross section, preferably square, and engages a complementary non-circular opening in a bushing 71 rotatively mounted at the bottom of the cylindrical member 56. The bushing 71 is provided with a worm wheel 72 which is engaged by a worm pinion 73 on a shaft 74 rotatively mounted upon the bracket 58 and the support 50. Spur gears 75 and 76 are mounted on the shafts 68 and 74, respectively, and mesh with each other.

The shaft 74 extends from the support 50 and is provided with a gear 78. This gear 78 is one of a train of meshing gears 79 mounted upon the back of the support 50. This train of gears 79 terminates in a drive gear 79' which is free on a bushing 94 turnably mounted on a stud 80 mounted on the support 50. An arm 81 is integral with the bushing 94 and projects radially along one side of the gear 79'. Another arm 81' is fixedly mounted on the bushing 94 and extends radially along the other side of the gear 79'. A gear 82' is mounted between the arms 81 and 81' and meshes with said gear 79'. The arm 81' has a bearing bushing 84 through which a shaft 83 extends. A gear 82 is mounted on shaft 83 and meshes with said gear 82'. The shaft 83 has a bearing in arm 81. The shaft 83 is provided with a friction drive wheel 86 which is adapted to engage the flywheel 20. A spring 87 is connected between the arm 81 and the support 50 and normally urges the arm 81 downwards so as to frictionally engage the friction wheel 86 against the flywheel 20. A casing 87' is mounted over the friction wheel 86. A brake spring 88 is mounted within the casing 87' a slight distance above the friction wheel 86 so that when the friction drive wheel 86 is lifted to disengage from the flywheel 20 it will engage the brake 88 and be instantly stopped.

The arms 81 and 81' have upwardly projecting lugs 90 upon which a horizontal depressible member 91 is mounted. This depressible member 91 has a stem portion 92 slidably engaged through the lugs 90. It has a head 93 at one end. A spring 95' is coaxially mounted on the stem portion 92 and acts between one of the lugs 90

and the head 93 for normally urging the stem portion 92 forwards. An element 95 projects from the slide 55 and is adapted to engage beneath the head 93 of the depressible member 91 when the slide 55 reaches its top position for lifting the arms 81 and 81' so as to disengage the friction drive wheel 86 from the flywheel 20. A rod 96 is turnably mounted in bearings 97 mounted on the support 58. A radial arm 98 is mounted on the rod 96 and has a substantially vertical slot 98' into which a pin 99 mounted on the stem portion 92 engages. An arm 100 is mounted on the rod 96 directly in front of the guard rod 36. The rod 96 is provided with a handle 101 by which it may be turned. When the guard rod 36 is in a raised position the handle 101 cannot be moved to cause the arm 98 to move the stem portion 92 rearwards because the arm 100 strikes the guard rod 36. When the guard rod 36 is in its bottom position the handle 101 may be moved to turn the rod 96 so that the arm 98 moves the stem portion 92 rearwards for moving the depressible member 91 rearwards and off the element 95. It should be noted that when the guard rod 36 is in a raised position it prevents the grindstones 32 sharpening the knife 15.

The grindstones 32 are rotatively supported on horizontal arms 105, 106, 107 and 108. The front ends of these arms pivotally engage upon the bottom portion 70' of the drive shaft 70, this bottom portion being circular so that said arms are free to pivot. The circular portion 70' of the main drive shaft 70 engages through a thrust bearing 110 which is mounted on the slide 55. The horizontal arms 105 and 106 are superimposed in respect to each other and support one of the grindstones 32, while the arms 107 and 108 are superimposed with respect to each other and support the other grindstone 32. A spring 112 is connected between the arms 105 and 107 for urging them towards each other. A spring 113 is connected between the arms 106 and 108 for urging them together.

The horizontal arms 105 and 107 are provided with upwardly extending fingers 114 which are provided with rollers 115 at their top ends. These rollers 115 engage the sides of a cam 116 mounted on the front of the hollow cover 30. The cam 116 has straight sides except at the bottom where it is formed into a pointed portion 117. The springs 112 and 113 maintain the rollers 115 against the sides of the cam 116. However, when the slide 55 moves downwards, and when the grindstones 32 are beneath the bottom of the hollow casing 30, then the rollers 115 reach the pointed portion 117 of the cam 116 and following the pointed portion 117 allows the springs 112 and 113 to move the grindstones 32 towards each other and against the knife 15.

A spur gear 120 is mounted upon the bottom portion 70' of the shaft 70 and meshes with a gear 121 mounted upon the arm 107 which in turn meshes with a gear 122 connected with one of the grindstones 32. The gear 120 also meshes with a gear 123 which meshes with a gear 124. These latter two gears 123 and 124 are mounted on the horizontal arm 105. The gear 124 meshes with a gear 125 mounted upon the other grindstone 32. The grindstones 32 are helical and the threads of the helixes are so arranged that when the grindstones 32 are together in sharpening position engaging the knife 15, the threads mesh with each other. Because of the helical form of the grindstones 32, the grinding operation will be continuous.

The operation of the device is as follows:

Normally, the grindstones 32 are in raised positions housed within the recessed bottom side portions 31 of the hollow cover 30. The depressible member 91 is held in a slightly raised position by the element 95. The friction wheel 86 is not contacting the flywheel 20. Now the electric motor 17 operates the crank pin 21 on the flywheel 20, and through the pitman 22, and the crosshead 23, reciprocates the knife 15. The cutting machine is used in this condition. When it is desired to sharpen the knife 15 the operator merely pivots the rod 96 by moving the handle 101. However, this cannot be done unless the presser foot 49 is in its extreme bottom position. It is necessary to move the presser foot handle 45 to cause the cam 44 to release the guard bar 36. Then the guard bar 36 drops to its bottom position and the presser foot 49 is now at its bottom position. When the handle 101 is moved the arm 98 is pivoted and because of the pin 99 on the stem portion 92 engaging the slot 98', the depressible member 91 is moved to a position in back of the element 95. The spring 87 now pivots the arms 81 and 81' downwards and engages the friction wheel 86 against the flywheel 20.

Rotations from the flywheel 20 will be transmitted by the friction wheel 86 to the gear 82, the gear 82', the drive gear 79', the train of gears 79, the gear 78, and the gears 75 and 76 to drive the shafts 68 and 74. The shaft 68 indirectly drive the cylindrical member 56. The shaft 74 indirectly drives the main drive shaft 70.

Rotations of the cylindrical member 56 causes the follower 60 to move the slide 55 downwards and then upwards back to its initial position. This represents one cycle of operation of the slide 55. During this cycle, while the slide 55 is moving downwards, the rollers 115 travel along the sides of the cam 116 until the grindstones 32 reach positions beneath the hollow cover 30. Now the springs 112 and 113 pivot the arms 105, 106, 107 and 108 and cause the grindstones 32 to move towards each other and engage the knife 15. The slide 55 continues downwards and during this period the knife 15 will be sharpened because the grindstones 32 are being driven. Rotations from the shaft 70 will indirectly drive the grindstones 32 in opposite directions because of the gear 120 and the trains of gears meshing with this gear.

When the slide 55 reaches its bottommost position it starts moving upwards. The grinding operation continues until the rollers 115 engage the point 117 of the cam 116. This separates the grindstones 32. When the slide 55 reaches its uppermost position the grindstones 32 will again be housed in the bottom recessed portions 31. The element 95 will come up and strike the bottom of the depressible member 91 lifting the arms 81 and 81' and causing the friction wheel 86 to disconnect from the flywheel 20. This automatically disconnects the sharpening means.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a cloth-cutting machine of the reciprocating knife type having a cross-head for the knife vertically slidably mounted in a housing, a nar-

row lug for supporting said knife projecting forwards centrally from said cross head, a hollow cover mounted on said housing and over said cross-head and having recessed bottom side portions for receiving grindstones for sharpening said knife, said recessed bottom side portions being positioned to the sides of said lug, a support mounted on the front of said hollow cover, a vertical slide slidably mounted on said support, horizontal arms pivotally mounted on said slide, grindstones mounted on said arms and normally disposed in said recessed bottom side portions, and cam means including a cam mounted on the front of said cover for moving said arms towards each other when said slide moves down a sufficient distance for said grindstones to clear the bottom of said hollow cover for engaging said grindstones against said knife.

2. In a cloth-cutting machine of the reciprocating knife type having a cross-head for the knife vertically slidably mounted in a housing, a narrow lug for supporting said knife projecting forwardly centrally from said cross head, a hollow cover mounted on said housing and over said cross-head and having recessed bottom side portions for receiving grindstones for sharpening said knife, said recessed bottom side portions being positioned to the sides of said lug, a support mounted on the front of said hollow cover, a vertical slide slidably mounted on said support, horizontal arms pivotally mounted on said slide, grindstones mounted on said arms and normally disposed in said recessed bottom side portions, and cam means including a cam mounted on the front of said cover and having straight sides and a pointed bottom portion for moving said arms towards each other when said slide moves down a sufficient distance for said grindstones to clear the bottom of said hollow cover for engaging said grindstones against said knife.

3. In a cloth-cutting machine of the reciprocating knife type having a cross-head for the knife vertically slidably mounted in a housing, a narrow lug for supporting said knife projecting forwards centrally from said cross head, a hollow cover mounted on said housing and over said cross-head and having recessed bottom side portions for receiving grindstones for sharpening said knife, said recessed bottom side portions being positioned to the sides of said lug, a support mounted on the front of said hollow cover, a vertical slide slidably mounted on said support, horizontal arms pivotally mounted on said slide, grindstones mounted on said arms and normally disposed in said recessed bottom side portions, and cam means including a cam mounted on the front of said cover and having straight sides and a pointed bottom portion for moving said arms towards each other when said slide moves down a sufficient distance for said grindstones to clear the bottom of said hollow cover for engaging said grindstones against said knife, said cam means also including upwardly projecting fingers on said horizontal arms for following said cam.

4. In a cloth-cutting machine of the reciprocating knife type having a cross-head for the knife vertically slidably mounted in a housing, a narrow lug for supporting said knife projecting forwards centrally from said cross head, a hollow cover mounted on said housing and over said cross-head and having recessed bottom side portions for receiving grindstones for sharpening said knife, said recessed bottom side portions being positioned to the sides of said lug, a support mounted on the front of said hollow cover, a ver-

tical slide slidably mounted on said support, horizontal arms pivotally mounted on said slide, grindstones mounted on said arms and normally disposed in said recessed bottom side portions, and cam means including a cam mounted on the front of said cover and having straight sides and a pointed bottom portion for moving said arms towards each other when said slide moves down a sufficient distance for said grindstones to clear the bottom of said hollow cover for engaging said grindstones against said knife, said cam means also including upwardly projecting fingers on said horizontal arms, and rollers on said fingers engaging the sides of said cam.

5. In a cloth-cutting machine of the reciprocating knife type having a vertical slide for moving grindstones along the knife for sharpening purposes, a support having guideways for said slide, a vertical cylindrical member rotatively mounted on said support and having an endless peripheral thread with a section extending down and continuing into a section extending up and connecting with the top of said downwardly extending section, means for rotating said cylindrical member, a follower mounted on said slide and engaging said endless peripheral thread for reciprocating said vertical slide, a main drive shaft for said grindstones extending coaxially through a hollow in said cylindrical member, a thrust bearing for said drive shaft mounted on said slide, and drive means for said main drive shaft, including a rotatively mounted drive bushing having an opening complementary to the shape of said main drive shaft through which said main drive shaft passes for non-rotative and slidable connection with the bushing, a worm wheel mounted on said drive bushing, and a worm pinion engaging said worm wheel.

6. In a cloth-cutting machine of the reciprocating knife type having a vertical slide for moving grindstones along the knife for sharpening purposes, a support having guideways for said slide, a vertical cylindrical member rotatively mounted on said support and having an endless peripheral thread with a section extending down and continuing into a section extending up and connecting with the top of said downwardly extending section, means for rotating said cylindrical member, a follower mounted on said slide and engaging said endless peripheral thread for reciprocating said vertical slide, a main drive shaft for said grindstones extending coaxially through a hollow in said cylindrical member, a thrust bearing for said drive shaft mounted on said slide, and drive means for said main drive shaft, horizontal arms pivotally mounted on said main drive shaft, grindstones mounted on said arms, and drive transmissions connecting said main drive shaft with said grindstones.

7. In a cloth-cutting machine of the reciprocating knife type having a vertical slide for moving grindstones along the knife for sharpening purposes, a support having guideways for said slide, a vertical cylindrical member rotatively mounted on said support and having an endless peripheral thread with a section extending down and continuing into a section extending up and connecting with the top of said downwardly extending section, means for rotating said cylindrical member, a follower mounted on said slide and engaging said endless peripheral thread for reciprocating said vertical slide, a main drive shaft for said grindstones extending coaxially through a hollow in said cylindrical member, a thrust bearing for said drive shaft mounted on said slide,

and drive means for said main drive shaft, horizontal arms pivotally mounted on said main drive shaft, grindstones mounted on said arms, and drive transmissions connecting said main drive shaft with said grindstones, and mounted on and extending along said horizontal arms.
